UNITED STATES PATENT OFFICE

140,964

DESIGN FOR A HANDLE FOR STOVE DOOR OR SIMILAR ARTICLE

Gustav Klein, Elkins Park, Pa.

Application January 12, 1945, Serial No. 117,387

Term of patent 7 years

(Cl. D10—8)

To all whom it may concern:

Be it known that I, Gustav Klein, a citizen of the United States, residing at Elkins Park, in the county of Montgomery and State of Pennsylvania, have invented a new, original, and ornamental Design for a Handle for Stove Door or Similar Article, of which the following is a specification, reference being had to the accompanying drawing, forming part thereof:

Fig. 1 is a top plan view of a handle for a stove door or similar article showing my new design.

Fig. 2 is a side elevation of the handle shown in Fig. 1.

Fig. 3 is a bottom plan view of the handle shown in Fig. 1.

I claim:

The ornamental design for a handle for stove door or similar article, as shown.

GUSTAV KLEIN.
